US00D697757S

(12) **United States Design Patent**
Xin

(10) **Patent No.:** US D697,757 S
(45) **Date of Patent:** ** Jan. 21, 2014

(54) **DETACHABLE AND REVERSIBLE GRILL PLATE**

(71) Applicant: **Xinhua Electric Appliance Co., Ltd.**,
Haiyan Zhejiang (CN)

(72) Inventor: **Ren Jian Xin**, Haiyan Zhejiang (CN)

(73) Assignee: **Xinhua Electric Appliance Co., Ltd.**,
Haiyan Zhejiang (CN)

(**) Term: **14 Years**

(21) Appl. No.: **29/437,801**

(22) Filed: **Nov. 20, 2012**

(51) LOC (10) Cl. **07-02**

(52) U.S. Cl.

USPC **D7/409**

OTHER PUBLICATIONS

Notice Allowance Mailed Mar. 25, 2013 for U.S. Appl. No. 29/437,628, filed Nov. 19, 2012; pp. 1–8.

Primary Examiner — Ricky Pham

(74) Attorney, Agent, or Firm — Dergosits & Noah LLP

(57) **CLAIM**

The ornamental design for a detachable and reversible grill plate, substantially as shown and described.

DESCRIPTION

FIG. 1 is a top perspective view of a detachable and reversible grill plate showing my new design.

FIG. 2 is a bottom perspective view thereof.

FIG. 3 is a top plan view thereof.

FIG. 4 is a bottom plan view thereof.

FIG. 5 is a rear elevational view; the front view is a mirror image thereof; and,

FIG. 6 is a side elevational view; the opposite side is a mirror image thereof.

1 Claim, 5 Drawing Sheets
